UNITED STATES PATENT OFFICE.

ABRAHAM DILLER AND JOSEPH W. WHITE, OF BRIGHTON, IOWA.

CAR-COUPLING.

SPECIFICATION forming part of Letters Patent No. 374,783, dated December 13, 1887.

Application filed September 9, 1887. Serial No. 249,222. (No model.)

To all whom it may concern:

Be it known that we, ABRAHAM DILLER and JOSEPH W. WHITE, both residents of Brighton, in the county of Washington and State of Iowa, have invented certain new and useful Improvements in Car-Couplings; and we do hereby declare that the following is a full, clear, and exact description of the invention, which will enable others skilled in the art to which it appertains to make and use the same, reference being had to the accompanying drawings, which form a part of this specification, and in which—

Figure 1 is a perspective view showing two railroad-cars provided with our new and improved coupling, and coupled together. Fig. 2 is a perspective view, on an enlarged scale, of the end of one of the cars provided with our coupling. Fig. 3 is a vertical transverse sectional view taken on the plane indicated by line *x x* of Fig. 4, and Fig. 4 is a longitudinal vertical sectional view taken on the plane indicated by line *y y* of Fig. 3.

The same letters of reference indicate corresponding parts in all the figures.

Our invention consists in a new and improved car-coupling, which will be hereinafter fully described and claimed.

Referring to the several parts by letter, A indicates the end of one car, which is provided with our new and improved coupling, and B indicates another car, also provided with our coupling.

The object of our invention is to enable the cars to be coupled together readily, easily, and surely without the necessity of going between them, and thereby prevent the loss of life which so frequently occurs from the train-men going between the meeting ends of the cars to couple them together.

To this end our invention consists in the new and improved construction, arrangement, and combination of parts, which will be hereinafter clearly described and claimed.

C indicates the draw-bar or bumper of each car or coupling, which is supported by the cross-supports D D, on which it slides, and has the usual spiral spring, E, arranged back of its inner rear end to form an elastic bumper when the cars come together, the stop F preventing the bumper or draw-bar from being

drawn out too far. This draw-bar of our coupling can be formed much smaller, narrower, and lighter than the usual draw bar or head of car-couplings, as there is no intricate mechanism mounted in it. Near its forward end the draw-bar is formed with the vertical opening G, which is cast slightly longer than its width in cross-section, so as to be oblong or rectangular in transverse section, and in and through this vertical opening fits the stem or shank H of the draft-hook I, the said stem being likewise formed longer than its width in cross-section, so that it will fit in the vertical opening G, and will thus, owing to its shape and that of the said opening, be prevented from turning in the said opening, thus always holding the point of the hook at precisely the same point. The point of the hook extends back, and is beveled on the under side of its extremity, as shown. Back of this hook the draw-bar is formed with the transverse opening J extending horizontally through it, and through this opening passes the bolt K, on the projecting ends of which the ends of the clevis or coupling-link L are pivotally mounted, so that the said link can be swung freely up and down. The hook I is retained removably in position in the vertical opening G of the draw-bar by the flat heavy key M, which passes through the transverse key-hole N in the lower end of the stem or shank of the hook, as shown, so that by removing the said key the hook can be removed, to be replaced by a new one, if broken, and also for the purpose hereinafter described.

On the top of the draw-bar, to the rear of the pivot-bolt K of the clevis or link, is cast a slotted eye, O, or rather two eyes or ears, between which the trigger-bar Q is pivotally secured by means of the pivot passing through the openings P P in the said ears.

Q indicates this trigger-bar, which is centrally pivoted by a pivot, Q', between the ears O O, as shown, so that its forward end, which is beveled on its upper side, will come in contact with the lower beveled side of the rearwardly-extending point of the draft-hook, and thus close the hook when the link of the other car has entered the same. The rear end of the trigger-bar passes back through into a recess, R, in the end of the car of the bumper plate or timber which is secured against the end of the car.

Through a bearing, S, in this end plate of the car passes the vertical operating-rod T, which may be formed at its upper end with a suitable handle for convenience in operating the coupling from the top of the car, the said rod being flattened at its lower end portion and there formed with the vertical slot U, through which the rear end of the trigger-bar passes, a key, V; passing transversely through the rear 5 extremity of the said bar to prevent the possibility of its working out of the slotted end of the lever, through which it slides as the draw-bar is moved in and out. The upper end of the slot in the lower end of the operating-rod is normally kept pressed down upon the rear end of the trigger-bar by means of a coiled spring, A', through which the rod T passes, the upper end of the said encircling coiled spring bearing against a stop or staple, 10 B', which holds the rod T in position, while its lower end bears down upon a transverse pin or stop, C', which is driven tightly through the said rod above the slot U, and it will thus be seen that the tension of this spring will 15 serve to keep the inner end of the trigger-bar always normally depressed and its forward beveled end raised in contact with the beveled point of the hook.

In operation, suppose the car A to be attached to the engine, while the other car, B, is to be coupled to car A, the links L of both cars hanging down loosely. The link of the car B is now turned up and back so that it rests against the end plate or end of the car above 20 the draw-head and sufficiently back of the same to prevent its falling until the cars come together. As the ends of the bumpers of the two cars strike together, the jar will throw the elevated link down, so that its outer end portion, or rather middle portion, will strike and rest upon the trigger-bar of the car A in front of the pivotal point of the same, when the weight of the link will depress and hold down the said forward end of the centrally-pivoted 25 trigger-bar, the spring A' yielding to the weight of the link. Now as the cars move apart the end of the link of car B will of course be drawn into the draft-hook of car A, when, as soon as its weight passes from the forward 30 end of the trigger-bar on entering the hook, the tension of the spring A' will force down the rod T, and through it the inner end of the centrally-pivoted trigger-bar, thus raising the forward part of the said bar until its beveled 35 end comes in contact with the beveled under side of the end or point of the draft-hook of car A, thus locking the link in the hook and effectually preventing it from being shaken or working out apart from the hook. When 40 the ends of the draw-bars come together in coupling, the bars are of course forced back, while when they separate their bumper-springs E force the said draw-bars out, and on both of these movements the rear end portions of the 45 trigger-bars slide through the slotted lower ends of the operating-rod T, and the said rods

are thus prevented from being bent or broken by the movements of the draw-bars, which carry the trigger-bars with them.

The cars are uncoupled by drawing up the upper end of the operating-rod T of car B, thus elevating the inner end and lowering the forward or outer end of the trigger-bar of the said car when the cars A and B are moved together so that the bumpers touch, when the end of the link of car B will be pushed or slid up the forward portion of the trigger-bar, which is shown in dotted lines in Fig. 1 in its depressed position, until the end of the link is back of the end of the draft-hook, when the rod T is pushed down to depress the inner end of the centrally-pivoted trigger-bar and raise the forward end of the same, when, as the cars are drawn apart, the end of the link will be drawn up the trigger-bar and off clear of the hook, the end of the trigger-bar being in contact with the end of the hook as the link is drawn over it by the separating cars.

The cars can also be uncoupled from the side of the car by means of a hand-lever or side lever, E', which is centrally pivoted, as shown, and hinged or swiveled at its inner end to the vertical operating-rod T, so that the trigger-bar can be operated as readily from the side as from the top of the car, as will be readily seen.

In order to enable cars provided with our improved coupling to be used on roads which are still using the common link-and-pin coupling, the draw-bar of each coupling is formed 100 with the recess F' extending in from its outer end, as shown in Fig. 4 of the drawings, and when a car provided with our coupling is used on a road where the cars use these ordinary 105 couplings all that will be necessary will be to remove the key from the lower ends of the draft-hooks, when the said hooks may be removed and a common pin substituted, or the stems of the said hooks will serve as coupling-pins for the common links, as will be readily 110 understood.

From the foregoing description, taken in connection with the accompanying drawings, the construction, operation, and advantages of our new and improved car-coupling will be 115 readily understood.

It will be seen that our new and improved coupling is simple, cheap, strong, and durable in construction and exceedingly safe and efficient in its operation. It will be seen that 120 a difference in the height of the cars will not interfere with the working of the coupling, and the coupling will couple as short as the common coupling now in use—that is to say, the distance between the cars when coupled 125 will be the same in both.

Should a clevis or link or a hook break on either car, they can be coupled together with the remaining link or hook without any delay, and the broken parts can be easily replaced at any time.

Having thus described our invention, what

we claim, and desire to secure by Letters Patent of the United States, is—

1. In a car-coupling, the combination, with the draw-bar, of the **U**-shaped link pivoted at its ends, the draft-hook having the beveled end, the centrally-pivoted trigger-bar having the beveled forward end and the key at its rear end, the vertical spring-actuated operating-rod having the slotted lower end, and the centrally-pivoted side lever, all substantially as and for the purpose herein shown and set forth.
2. In a car-coupling, the combination, with the sliding spring-actuated draw-bar, of the **U**-shaped link pivoted at its ends, the draft-hook having the beveled point, the centrally-pivoted trigger-bar having the beveled forward end and the key at its rear end, and the vertical spring-actuated operating-rod having the slotted lower end, substantially as set forth.
3. In a car-coupling, the combination, with the sliding spring-actuated draw-bar formed

with the end recess, the vertical end opening, and the perforated ears, of the **U**-shaped link pivoted at its ends, the removable draft-hook having the beveled point, the centrally-pivoted trigger-bar having the beveled forward end and the key at its rear end, the vertical spring-actuated operating-rod having the slotted lower end, and the centrally-pivoted side lever, all substantially as and for the purpose herein shown and set forth.

In testimony that we claim the foregoing as our own we have hereunto affixed our signatures in presence of two witnesses.

ABRAHAM DILLER.
